(No Model.)

G. E. SMITH & F. P. GARRISON.
COPY HOLDER.

No. 556,650.

Patented Mar. 17, 1896.

UNITED STATES PATENT OFFICE.

GEORGE E. SMITH AND FRANK P. GARRISON, OF WESTWOOD, OHIO.

COPY-HOLDER.

SPECIFICATION forming part of Letters Patent No. 556,650, dated March 17, 1896.

Application filed January 3, 1896. Serial No. 574,232. (No model.)

To all whom it may concern:

Be it known that we, GEORGE E. SMITH and FRANK P. GARRISON, of Westwood, in the county of Hamilton and State of Ohio, have 5 invented a new and Improved Copy-Holder, of which the following is a full, clear, and exact description.

This invention relates to certain improvements in copy-holders such as are employed 10 by type-writers and others for holding copy in position; and the object of the invention is to provide a device of this character of a simple and inexpensive construction, which shall be light and strong and adapted to be securely 15 fastened to a table or desk in position for use and which shall be adjustable, so as to enable the copy to be held in any position desired.

The invention consists in certain novel features of construction and combinations which 20 will be fully described hereinafter and finally embodied in the claims.

Reference is to be had to the accompanying drawings, forming a part of this specification, in which similar characters of reference indicate 25 corresponding parts in all the views.

Figure 1 is a side view showing our improved copy-holder in position for use. Fig. 2 is a face view of the same. Fig. 3 is a sectional plan view of the device, taken in the plane 30 indicated by the line *a a* in Fig. 1. Fig. 4 is a fragmentary sectional view taken vertically through the lower part of the standard of the device. Fig. 5 is a transverse fragmentary sectional view taken through the copy-holding 35 frame in the plane indicated by the line *b b* in Fig. 1; and Fig. 6 is a view similar to Fig. 5, but taken in the plane indicated by the line *c c* in Fig. 1.

In carrying out our invention we prefer- 40 ably provide a base 1 of suitable construction, which may be adapted to be secured rigidly to a desk or table by means of screws 2, as indicated in the drawings, or may be of sufficient weight to hold the copy-holding frame 45 without being thus secured to a desk or table, and said base 1 is provided with a socket 3, formed in its upper part and adapted to receive the lower end of a standard or supporting-bar 4, clamped in said socket by means 50 of a set-screw 5 and extending vertically, as shown in the drawings.

On the bar or standard 4 is mounted to slide

a collar or runner 6, having a set-screw 7 for securing it in place, and said collar or runner is provided with an arm 8 extending from it 55 and having its free end forked to receive the end of a swinging section 10, pivoted thereto, as indicated at 9, and having its outer end pivotally connected to a pivot-block 12, as shown at 11.

The pivot-block 12 is provided with lugs 13, projecting from its upper face, said lugs being spaced apart and adapted to receive between them a set-screw 15, extending between forks 14 projecting from the rear side 65 of the copy-holding frame, whereby it will be seen that the said frame is held to swing pivotally on said pivot-block 12, and is capable of being clamped by means of a set-screw 15 when in position for use. The pivot-pin 11, 70 whereon the pivot-block swings, is arranged vertically, while the pivot-pin 15, whereon the copy-holding frame swings, is arranged horizontally.

The copy-holding frame is provided with 75 parallel side bars 16, spaced apart to form between them a guideway 17, wherein slides the shank 18 of the support 19 for the upper portion of the copy, said support being, as shown in Fig. 2, of a general T form and 80 being held in place in the guideway 17 by lugs 20 projecting from the front faces of the side bars 16 at the upper ends thereof and bearing against the front side of the shank 18, while at the rear side of the copy-holding 85 frame said side bars 16 are connected together at their upper portions by a transversely-extending solid web 21, wherein is carried a set-screw 22 having engagement with the rear face of the shank 18 and adapted when op- 90 erated to clamp the support 19 in position on the copy-holding frame. At the lower portion of the frame the same is provided with a cross-bar 23 projecting from its opposite sides and having arms 24 extending forwardly 95 at right angles from its ends, between which arms extends a pivot-pin 25, whereon is mounted a clamping-bar made in a general U form and having its end portions 26 pivotally mounted on the pivot-pin 25, while its central portion 27 is bent forwardly, as indicated in Figs. 1 and 3, so as to permit the upper ends of its side portions 26 to engage lugs 28 projecting from the side bars 16 at

their central portions. Springs 29 are employed to hold the clamping-bar pressed with its upper end against the lugs 28, said springs being coiled on the pivot-pin 25 and having 5 their opposite ends connected to the ends 26 of the clamping-bar and to the arms 24 of the frame, respectively.

In operation it will be seen that the runner 6 may be adjusted vertically on the standard 10 4 so as to permit the copy to be held at any desired elevation, and the copy-holding frame may be swung horizontally on the pivot 9, as indicated in dotted lines in Fig. 3, so as to bring it in any desired position, while said 15 frame may be also swung upon the pivot 11 so as to vary the angle at which it stands relatively to the section 10. The angle to the vertical at which the copy is held may also be varied by means of the set-screw 15, and 20 the support 19 for the upper part of the copy may be raised or lowered at will to accommodate different-sized sheets. Moreover, the spring-actuated clamping-bar of the copy-holding frame is so constructed that the 25 frame is adapted to hold books, said bar being arranged to bear on each side of the book when the same is open.

From the above description it will be seen that the device is of an extremely simple and 30 inexpensive construction and is well adapted for the purpose for which it is intended, and it will also be obvious that the device is susceptible of considerable modification without material departure from the principles and 35 spirit of the invention, and for this reason we do not wish to be understood as limiting ourselves to the exact form of the device herein set forth.

Having thus described our invention, we 40 claim as new and desire to secure by Letters Patent—

1. In a copy-holder, the combination with a standard, of a runner movable on the stand-

ard, an arm connected to swing horizontally on the runner, a copy-holding frame pivotally connected to the arm and movable on a horizontal axis, the frame comprising two vertical bars having a web at their upper portion, the web being contiguous to an inwardly-extended lug, a slide movable between the bars and held by the web and lug, a set-screw carried by the web and engaging the slide, a transverse bar at the lower end of the copy-holding frame, and a spring clamping-bar held by the transverse bar, substantially as described.

2. In a copy-holder, the combination with a support, of a copy-holding frame having two parallel side bars connected at their upper ends by a web and one of the side bars having a lug, a slide movable between the side bars and confined by the web and lug, a set-screw carried by the web and engaging the slide, and a spring clamping-bar held at the lower portion of the frame, substantially as described.

3. In a copy-holder, the combination with a support, of a copy-holding frame having two parallel side bars connected at their upper portion by a web and one side bar having a lug, a slide movable between the side bars and held by the web and lug, a set-screw operating in the web and engaging the slide, the side bars each having an outwardly-projecting lug and the copy-holding frame having at its lower end, a transverse cross-bar, a pivot-pin carried by the cross-bar, and a spring clamping-bar pivoted on said pin and adapted to engage the lugs of the parallel bars, substantially as described.

GEORGE E. SMITH.
